ROCK THROWER

George C. Kohlmier, Owatonna, Minn.

Application October 4, 1952, Serial No. 313,101

1 Claim. (Cl. 209—260)

1

My invention relates broadly to improvements in rock crushing machinery of the type which crushes or breaks up only rocks above a given size. In machinery of this type loads of gravel, from a gravel pit or the like, are deposited initially into a hopper from which the gravel is conveyed to the rollers where rocks above a given size are crushed. Because rocks above a given size place undue wear and stress upon the crushing rollers, it is conventional to provide a screen above the hopper to prevent passage into the hopper of all rocks above a given size. Frequently this screen becomes partially clogged by the large rocks. In such a case it is necessary to shut the machinery down while one of the workers manually lifts the large rocks from the surface of the screen—or alternatively to risk injury to the workers between dumpings of the scoop-shovel.

The primary object of my invention is the provision of a mechanism for mounting the screen whereby the same may be swung from its normal position overlying the hopper to a rock dumping position more than 90° therefrom.

A still further object of my invention is the provision of a novel manually controlled power mechanism for imparting rock throwing movements to said screen.

A still further object of my invention is the provision of a device of the type immediately above described which is inexpensive to produce, is rugged in construction, is durable in use and has but a minimum of working parts.

The above and still further objects of my invention will become apparent from the following detailed specification, appended claims, and attached drawings.

Referring to the drawings wherein like characters indicate like parts throughout the several views:

Fig. 1 is a view in side elevation of my novel structure;

Fig. 2 is an enlarged fragmentary view in side elevation taken from the opposite side of Fig. 1 and showing a different position of some of the parts;

Fig. 3 is a fragmentary top plan view as seen substantially from the line 3—3 of Fig. 1;

Fig. 4 is a fragmentary view partly in plan and partly in horizontal section, taken substantially on the line 4—4 of Fig. 1, some parts being broken away and some parts indicated by dotted lines; and

Fig. 5 is a fragmentary detail of the crank arm—pitman arm connection of my invention, some parts being broken away and some parts being shown in section.

2

Referring with greater particularity to the drawings, the numeral 1 indicates in its entirety suitable framework of the loading end of a rock crusher. Suitably secured to the frame 1 is a hopper 2 into which gravel A, as it comes from a gravel pit, is deposited through the medium of a scoop-shovel or the like B. Normally overlying the hopper 2 is a rigid screen, identified in its entirety by the numeral 3, and comprising a rigid 10 rectangular frame 4 and cross-members 5 providing rectangular openings 6 of a desired size. At its rear end the screen 3 is pivotally secured to a transverse shaft 7, as indicated at 8, for swinging movements on a horizontal axis. Extending transversely through the frame 1 below the hopper 2 is a rotary shaft 9 to one end portion of which, for common rotation therewith, is secured a sprocket wheel 10. Secured to opposite ends of said shaft 9 is a pair of matching crank 20 arms 11. A pair of pitman arms 12 have their opposite ends secured to the outer ends of said crank arms 11, as at 13, and to the frame 4 of the screen 3, as indicated at 14. It will be noted that the pivotal connection 14 is forwardly spaced with relation to the pivotal connection 8 of the screen 3 to the hopper 2. It will also be noted that the relationship, location and length of the crank arms 11 and pitman arms 12 is such that, upon rotation of the shaft 9, the screen 3 will be swung from the normal horizontal position of Fig. 3 to the full line rock-dumping position of Fig. 2—more than 90° of arc therefrom. As shown in Fig. 4, the shaft 9 is journaled in spaced bearings 15 in longitudinally extended frame member 16.

Spaced forwardly from the shaft 9, in substantially the same horizontal plane therewith, is a rotary drive shaft 17 having its intermediate portion journaled in spaced bearings 18 secured to the horizontal frame members 16. Rigidly secured to one end of the drive shaft 17, for common rotation therewith, is a sprocket wheel 19. A drive chain 20 runs over sprocket wheels 10 and 19. Journaled for rotation on the opposite end of the drive shaft 17 is a power operated driving member or sprocket wheel 21 having a clutch element 22 associated therewith. A collar 23 is mounted on the shaft 17 for limited sliding movements with respect thereto, whereby to engage and disengage a clutch element 24, carried thereby, with the clutch element 22 associated with the sprocket wheel 21. As shown, the collar 23 is provided with a pair of laterally-spaced circular flanges 25 which provide an annular recess 26 for the reception of opposed roller elements 27 carried by the outer end of a bifurcated tongue

28, see Figs. 1 and 4. As shown, particularly by reference to Fig. 1, the upper end of the tongue 28 is rigidly secured by means of a nut or the like 29 to one end portion of a rock shaft 30 journaled in suitable bearings 31 in the frame 4. Also, as shown, the rock shaft 30 is provided with a radially projecting handle 32.

As shown, a source of power is provided for the sprocket wheel 21 through a medium of a chain 33 which runs thereover and over a sprocket wheel 34 mounted on a shaft 35. Shaft 35 is rotated by means of a source of power not shown.

When gravel from a scoop-shovel like B is dumped onto the screen 3, as shown in Fig. 1, all but rocks above a given size will be allowed to pass through the openings 6 therein. All rocks above this size will be retained on the upper surface of the screen 3. Between periodic dumpings of the scoop-shovel B, these large rocks may be quickly and easily removed by the operator's merely pulling inwardly upon handle 32 while standing on a platform X whereby to rock the shaft 30 and the bifurcated tongue 28 in the same direction, thereby causing the collar 23 to slide outwardly on shaft 17 to bring about engagement between the cooperating clutch elements 22 and 24. The pin 36 carried by the shaft 17 and the slot 37 in the collar 23 permit of this sliding movement between these two elements while tying the same together for common rotation. When rotation is imparted to the shaft 17 through interlocking of the clutch elements 22 and 24, rotary movement is also imparted to the shaft 9 through chain 20 and sprocket wheel 10. Rotation of the shaft 9 causes the crank arms 11 and the pitman arms 12 to elevate the forward end of screen 3 on the pivot 8 to the full line position of Fig. 2, wherein the large rocks are dumped off under the action of gravity. A complete rotation of the sprocket wheel 10 will bring the screen 3 back to its normal horizontal operative position overlying the hopper 2. At this point, the operator pushes outwardly upon the handle 32 whereby to restore the handle to its normal inoperative vertical position so as to cause disengagement between the cooperating clutch elements 22 and 24. Thereafter, the sprocket wheel 21 rotates freely upon the shaft 17 until it is next desired to impart dumping or rock throwing movements to the screen 3.

While I have disclosed a preferred embodiment

of my invention, it should be obvious that same is capable of modification without departure from the scope of the invention as defined in the appended claim.

5 What I claim is:

In a device of the class described, a frame including laterally spaced parallel horizontally disposed frame members, a normally horizontal rigid screen supported by said frame, means pivotally mounting one extreme end of said screen between said frame members for swinging movements from and back to said normal horizontal position about a horizontal axis, a rotary shaft in said frame below said screen and extending transversely thereof, a crank arm on one end of said shaft, a pitman arm having its opposite ends pivotally connected to the outer end of said shaft and to said screen forwardly of the pivotal mounting thereof, said crank arm and pitman being of a length to swing said screen from its normal horizontal position to a dumping position slightly in excess of 90° of arc therefrom, a power operated mechanism for imparting movement to said rotary shaft comprising a drive shaft, a power operated driving member journaled on said driving shaft, a clutch element associated with said driving member, a collar mounted on said drive shaft for common rotation therewith and for limited axial movements with respect thereto, a second clutch element associated with said collar and engageable with said first-mentioned clutch element on axial movements of said collar in one direction, means for shifting said collar on said shaft to cause engagement and disengagement between said clutch elements, and driving connections between said drive shaft and said rotary shaft.
